UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

RAM-BOX MECHANISM FOR STOKERS.

Application filed June 4, 1923. Serial No. 643,366.

To all whom it may concern:

Be it known that I, OTTO ARAM, a citizen of the United States, and a resident of Philadelphia, in the county of Philadelphia and State of Pennsylvania, have invented a new and useful Improvement in Ram-Box Mechanism for Stokers, of which the following is a specification.

My invention relates to a ram box assembly for mechanical stokers, particularly of the underfeed type, and it has for its object to provide apparatus of the character designated which may be simply and cheaply manufactured, which may be readily installed and repaired, and which shall permit of taking up ram box wear with great facility.

In my prior application, Serial No. 638,119, filed May 10, 1923 and assigned to Westinghouse Electric and Manufacturing Company, I disclose and claim a mechanical stoker of the underfeed multi-retort type wherein the separate retort structures are each carried by a pair of angle beams, the retort structures resting within and being embraced by said angle beams.

In accordance with the present invention, I carry said angle beams forwardly through the front wall of the stoker and employ them for supporting the respective hoppers and ram box mechanisms.

Furthermore, by mounting a frame member across the forwardly-projecting ends of the angle beams for a plurality of retorts, and by mounting the driving crank shaft and ram boxes for the respective retorts upon this frame member, I am enabled to line up the crank shaft with facility and I am also enabled to secure proper alignment between the respective cranks and their associated ram boxes, as is essential for proper drive of the rams.

In the accompanying drawing, Fig. 1 is a side view, taken along the center line of a retort of a mechanical stoker of the underfeed type, embodying a front wall structure involving my invention; Fig. 2 is an exploded view of the ram box lining structure employed in accordance with my invention; Fig. 3 is a front elevation of the main frame casting employed in the stoker of Fig. 1; Fig. 4 is a partial plan view of the frame shown in Fig. 3; Fig. 5 is a transverse sectional view on the line V—V of Fig. 1 and

Fig. 6 is a front elevation of the end of one of the retorts with the bracket 23 removed.

Referring to the drawing for a more detailed understanding of my invention, I show a stoker structure 10 of conventional form embodying a retort 11 and air feeding tuyères 12. The retort structure is carried by angle beams 13 as fully disclosed in the aforementioned application. Said angle beams are carried forward through the front wall 14 and terminate, as indicated, at 15.

A hopper casting 16 is provided for each retort and nests within the associated angle beams, this hopper casting carrying the usual hopper 17.

A main front frame member 18, shown more clearly in Figs. 3 and 4, is mounted across the front of a plurality of retorts and is shown in Fig. 3 as being of such size as to provide for three retorts. The frame member 18 has a pair of rearwardly extending flanges 19—19 for each retort, and these flanges are adapted to be fastened to the angle beams for each retort by suitable bolts as indicated at 20—20 in Fig. 1. The flanges 19—19 associated with each retort are joined by an arch 21 serving to strengthen the same and to define a ram box supporting structure. The rear portion of the crown of this arch is bolted to the hopper casting as shown at 22 in Fig. 1, in order to stiffen the entire device.

From the foregoing, it will be obvious that the frame member 18 serves to tie together and to line up the forwardly-projecting ends of the respective angle-beams in order to tie the operating mechanism into a coordinate whole. Thus, suitable brackets 23 may be mounted upon the frame member and carry a conventional ram driving crank shaft 24, and similarly, ram box sleeve members may be carried by, and aligned from, the frame member 18 for each retort so that proper alignment thereof with the respective cranks may be readily secured.

The ram box sleeve structure comprises in its essence a lower member 25 and an upper member 26 separated by shims 27—27, all as clearly indicated in Fig. 2. The lower member 25 is first seated within the angle irons for the associated retort and is bolted thereto as indicated at 28 and 29. The upper member 26 is then slipped in place and an upwardly-projecting slotted lug 30 there-

upon engaged within a notch 31 in the frame member 18, this notch being most clearly shown in Fig. 4. The shim members 27-27 having been placed in position, 5 clamping screws 32-32, shown most clearly in Fig. 4, are forced down upon suitable steps, one of which is indicated at 33 in Fig. 2, thus forcing the upper member 26 toward the lower member 25 to define a 10 cylindrical ram box structure for the reception of a suitable operating ram. A bolt 34 is then placed through the member 18 and the slotted lug 30 to firmly secure the member 26 in place.

15 It is well-known that the wear in ram boxes is mainly at the bottom thereof because of the weight of the ram and the grinding action of dust and dirt, and it follows that the box soon wears to an oval 20 cross section with the major axis in a vertical direction. In order to compensate for such wear, the upper member 26 may be loosened, thinner shims 27-27 inserted, and the upper member 26 again tightened in 25 place, when it will be found that a close fit of the ram is again secured.

While I have shown my invention in but one form, it will be obvious to those skilled in the art that it is not so limited, but is 30 susceptible of various changes and modifications, without departing from the spirit thereof, and I desire, therefore, that only such limitations shall be placed thereupon as are imposed by the prior art or as are 35 specifically set forth in the appended claims.

What I claim is:

1. In an underfeed stoker embodying a plurality of retorts, longitudinally extending supporting members for said retorts, 40 said members projecting outwardly through the front wall of the stoker, a laterally extending frame carried by the ends of said projecting members and projecting across a plurality of retorts, and a ram-driving crank-shaft carried by said frame.

2. In an underfeed stoker embodying a plurality of retorts, longitudinally extending supporting members for said retorts, 50 said members projecting outwardly through the front wall of the stoker, a laterally extending frame carried by the ends of said projecting members and projecting across a plurality of retorts, and a ram-box sleeve structure for each retort fastened to said frame.

3. In an underfeed stoker embodying a plurality of retorts, longitudinally extending supporting members for said retorts, 60 said members projecting outwardly through the front wall of the stoker, a laterally extending frame carried by the ends of said projecting members and projecting across a plurality of retorts, and a ram box sleeve structure for each retort fastened to each frame, said structure being formed in an

upper and a lower member with shim members therebetween.

4. In an underfeed stoker embodying a plurality of retorts, longitudinally extending angle beams for supporting said retorts, 70 said beams projecting forwardly through the front wall of said stoker, a laterally extending frame member projecting across a plurality of retorts in front of said stoker and having rearwardly extending flanges attached to said beams respectively, and a ram box sleeve structure for each retort fastened to said frame member, said sleeve structure resting between the angle beams for the associated retort.

5. In an underfeed stoker embodying a plurality of retorts, longitudinally extending supporting members for said retorts, 80 said members projecting outwardly through the front wall of the stoker, a laterally extending frame carried by the ends of said projecting members and projecting across a plurality of retorts, a hopper casting for each retort, and fastening means between each hopper casting and said frame.

6. In a fuel-feeding device for a mechanical stoker, a ram box embodying a lower member, a superposed upper member, a frame surrounding said members to which one of said members is attached, clamping members attached to said frame and adapted to force the remaining member toward said attached member, and shims between said two members.

7. In a fuel-feeding device for a mechanical stoker, a ram box embodying a lower member, a superposed upper member, a frame surrounding said members to which said lower member is attached, clamping screws passing through said frame and adapted to force said upper half toward said lower half, and shim members between said two members.

8. In a fuel-feeding device for a mechanical stoker, a ram box embodying a lower member, a superposed upper member, a frame surrounding said members to which said lower member is attached, slotted fastening means between said upper member and said frame, clamping means engaging said frame and adapted to force said upper member toward said lower member, and shims between said two members.

9. In an underfeed stoker embodying a plurality of retorts, a pair of angle beams 120 supporting and embracing each retort structure, said angle beams projecting through the front wall of the stoker, a hopper casting for each retort resting between the associated angle beams and having a ram box opening, a frame extending across the front of a plurality of retorts and having rearwardly extending flanges for engaging the respective angle beams, said frame being 125 provided with a ram box opening adjacent 130

each retort, a lower ram box member for each retort fastened to said frame and to the associated hopper casting, an upper ram box member surmounting each lower member and engaging said frame in a slotted connection, clamping means carried by said frame and arranged to force said upper

member downwardly upon said lower member, and shims between said two members.

In testimony whereof, I have hereunto 10
subscribed my name this 25th day of May,
1923.

OTTO ARAM.
